UNITED STATES PATENT OFFICE.

ADA H. VAN PELT, OF OAKLAND, CALIFORNIA, ASSIGNOR OF ONE-HALF TO
C. L. MAXWELL, OF SAME PLACE.

HOUSE-DOOR LETTER-BOX.

SPECIFICATION forming part of Letters Patent No. 471,918, dated March 29, 1892.

Application filed June 4, 1891. Serial No. 395,097. (No model.)

To all whom it may concern:

Be it known that I, ADA H. VAN PELT, a citizen of the United States, residing at Oakland, Alameda county, State of California, have invented an Improvement in Letter-Boxes; and I hereby declare the following to be a full, clear, and exact description of the same.

My invention relates to certain improvements in letter-boxes which are especially adapted for receiving mail-matter.

It consists in certain details of construction, which will be more fully explained by reference to the accompanying drawings, in which—

Figure 1 is a perspective view of the box closed. Fig. 2 is a view of the box open. Fig. 3 is a vertical section.

In the construction of letter-boxes for the reception of mail-matter it is desirable to provide a box which can be easily attached to the door or other point without unduly marring the wood-work or place to which it is attached, to make the box water and dust proof and at the same time leave its contents discernible from the outside, to make the operative parts so nearly automatic that but little difficulty will be experienced in operating them, and at the same time to make the box of as small bulk as possible.

In the construction of my box I make the main body or frame A, having two vertical sides, with suitable connecting parts at top and bottom. The top plate B is made with two separate angles, the upper portion being the steepest, as here shown. It has also a small inclination toward one side, so that the tendency of water will be to flow off in the angle between the two inclines. Beneath this incline is hinged the flap C, the outer surface of which is inclined and curved, as shown, and the inner edge projects beneath the overlapping incline B of the top bar. The outer front portion of this flap projects beyond the pivot-pins, by which its ends are attached between the sides A of the box, and the weight of the outer portion is such that the inner edge will be constantly closed up beneath the inclined top plate B and thus form a practical continuation of this bar, over which water can freely flow in case the box is exposed to

rain, and at the same time a practically dust-tight joint is made between the upper inner edge of the flap C and the lower portion of the plate B. By reason of the less inclination of the lower part of the plate B the front edge is made considerably thicker and projects sufficiently above the flap C to form a guide, so that when a letter is placed with its side against this edge pressure upon the letter will cause the flap to tilt, so as to allow the letter to slide into the box, and the flap will immediately return to its position by gravitation. By this construction only one hand need be used by the postman or other person dropping a letter.

The front of the box D is made of ornamental open-work, through which the interior of the box is easily visible, and upon the interior of this front plate is fixed a glass plate E, which covers the open-work, so that while one can easily see through and inspect the interior of the box all dust and moisture are effectually excluded therefrom. To the lower portion of this front is attached the curved box F, open at the top for the reception of papers, and it also serves as a receptacle for letters and papers for mailing. At a convenient point upon the front I fix the name-plate of the owner.

The lower portion of the front D and the part F have the exterior projecting lugs G and the bottom of the posts A have corresponding projecting feet H, through which the pivot-pins I pass to attach the lugs G to these projections H. By reason of these projecting lugs the greater portion of the weight of the movable door or front is thrown behind the vertical plane of the pivot-pins I, so that when the front is opened outward it turns about these pivot-pins and occupies the position shown in Fig. 2. In this position the contents of the box are easily taken out, as they will fall forward and lie upon the inner side of the front D and may be removed when the front is opened outward, as shown in Fig. 2. As soon as the front is released the weight of the rear portion, which is behind the pivot-pins I, is sufficiently greater than that of the upper portion so that the door will close by gravitation. This door is provided with a spring-lock of any suitable or convenient pattern, so

that as soon as it is released after being opened it closes and locks itself.

At the inner side and bottom of the front D is the bottom D', upon which the letters 5 rest when dropped into the box, and upon each side are the upturned lugs or flanges D². These flanges serve to retain the letters in place on the front D whenever this front is tilted forward for the purpose of removing the letters, 10 and the flanges prevent the letters from slipping out to either side until they can be properly removed. The bottom also serves to throw the contents of the box forward as the door or front is opened, and thus makes it convenient 15 to take the letters out.

The arched front F, which is secured to the lower part of D to contain papers, as before described, is also provided with a bottom upon which the papers rest, and this front being se- 20 cured to the front D these parts all move in unison when the front or door is opened.

In order to prevent the door opening to a point beyond what is necessary to remove the letters and to insure its closing again by gravita- 25 tion I have shown lugs J, which project in any suitable manner from the bottom to the front D and engage the projecting feet H when the door has been opened to a sufficient distance, these lugs acting as stops for the 30 purpose above stated. The hinged flap C is also provided with similar stops C', which prevent the flap turning too far when a letter is introduced and insure its closing by gravita- tion.

35 Cross-bars within the body A, extending across the upper and lower part and at the back, have screw-holes made in them, through which screws are introduced to secure the box to its position, and as these are entirely con- 40 cealed within the box when closed it is im- possible to remove it from its place by any ordinary means.

A letter-box thus constructed occupies the least possible depth from the face of the door 45 outwardly, and provides a very perfect, safe, and tight receptacle for letters and papers.

Having thus described my invention, what I claim as new, and desire to secure by Letters Patent, is—

50 1. In a letter-box, the main frame secured to the door or other support and having the outwardly-projecting feet at the bottom, the door or front having corresponding projections or lugs at its lower front portion, said door or front having a rearwardly-extending bottom, and pivot-pins at the front of the door uniting the projecting feet thereof with those of the frame, whereby the weight of the door is thrown to the rear of the vertical 55 plane of the pivots, so that when the door is opened outward it will close by gravitation, substantially as herein described.

2. In a letter-box, the main frame with means for securing it to a door or support, a 60 front having perforations through which the interior may be inspected, a glazed covering by which these openings are hermetically

sealed, a rearwardly-extending bottom con- 70 nected with this front, upon which letters dropped into the box are received, inwardly- projecting sides or flanges to retain letters in place when the front is opened, lugs pro- jecting from the lower front edge of the door, and corresponding projections or feet upon the main frame with pivot-pins by which the 75 two are united, and a hinge formed around which the door may be moved in a vertical plane to open it and about which it moves by gravitation when released so as to close, sub- 80 stantially as herein described.

3. In a letter-box, the main frame having a combined door and receptacle pivoted or hinged to its lower front portion, and a lock by which the upper front edge of the door is engaged with the top of the main frame to re- 85 ceive the box, in combination with a flap C, pivoted to the upper part of the main frame, so that the inner edge extends beneath the top of said frame, and the outer edge weighted, so that the flap is closed and retained by 90 gravitation, substantially as herein described.

4. In a letter-box, the main frame having cross-bars, a means for attaching it to the door or support, the door or front forming a containing-box for letters having its front lower 95 edge pivoted between the front lower sides of the main frame, so as to turn about said pivots in a vertical plane, an inclined top plate extending across the upper ends of the main frame, a flap pivoted between the sides of the 100 main frame, having that portion exterior to the pivots made heavier than the inner portion, said inner portion extending beneath the inclined top plate of the main frame and forming therewith a continuous roof or wa- 105 ter-shed, and a dust-tight joint, substantially as herein described,

5. In a letter-box, the main frame secured to the door or support, having an inclined top plate, a weighted flap pivoted between the 110 sides of the main frame beneath the top plate, with the portion exterior to the pivot-pins made heavier than the interior portion, said interior portion extending beneath the top plate of the main frame and having a lug 115 which limits the amount of opening whereby the flap may be opened inwardly by the pressure of a letter and closed again by gravitation after the letter has passed, a door or front having bottom and sides projecting in- 120 wardly and forming a receptacle for letters thus introduced, pivot-pins connecting the lower front portion of said door with the ex- 125 tensions of the main frame, whereby the door may be opened outwardly from the top in a vertical plane and closed by gravitation when released, and lugs J, by which the distance to which the door is opened is limited, substan- tially as herein described.

6. In a letter-box, the main frame, with 130 means for securing it to a door or support, a top plate, a pivoted automatically-closing flap which opens inwardly to pressure for the reception of letters and closes by gravi-

tation, a door or front having inwardly-projecting bottom and sides forming a receptacle for letters thus introduced, and a curved front exterior to the lower part of said door
5 for the introduction of papers or other matter, extensions from the lower front portion of the main frame, corresponding lugs extending from the lower front portion of the door or front, and pivot-pins by which these
10 are united or fulcrumed to the main frame,

and lugs to limit the opening of the door, so that the latter will close by gravitation when released, substantially as herein described.

In witness whereof I have hereunto set my hand.

ADA H. VAN PELT.
